UNITED STATES PATENT OFFICE.

JOHN M. DICKSON, OF INDIANAPOLIS, INDIANA.

DOLL-HEAD.

1,027,324.

Specification of Letters Patent. Patented May 21, 1912.

Application filed February 12, 1912. Serial No. 677,097.

To all whom it may concern:

Be it known that I, JOHN M. DICKSON, a citizen of the United States, residing at Indianapolis, in the county of Marion and

5 State of Indiana, have invented a new and useful Doll-Head, of which the following is a specification.

The present invention relates to improvements in doll heads, the primary object of 10 the invention being the provision of a novel means, whereby a different pair of eyes may be disposed successively or consecutively through the eye apertures in the head of a doll or other lay-figure, a peculiarly arranged mechanism being disposed within 15 the head of the doll or figure and controlled by weight actuated and ratchet mechanism, whereby upon the movement of the head to reclining position, the weight actuated 20 mechanism will be actuated to present upon the up-righting of the head, a pair of eyes with the different characteristics from the eyes just presented.

A further object of the present invention 25 is the provision of a pair of eye carrying drums keyed upon and rotatable with a shaft disposed transversely within the head of the figure, each of said drums being provided with a plurality of peripherally disposed eyes so arranged as to be presented in 30 pairs to the respective apertures provided in the head of the figure, there being a weight actuated lever operably connected to the spindle and in co-active relation to the 35 drum, so that when the head of the figure is tilted to reclining position, it is released from the drum and when returning to an upright position, to engage to rotate the drums to present another pair of eyes to the 40 eye apertures in the head of the figure, there being a locking device operably connected to the spindle for preventing the too far rotation of the drum at each reclining and up-righting of the head.

45 With the foregoing and other objects in view which will appear as the description proceeds, the invention resides in the combination and arrangement of parts and in the details of construction hereinafter described 50 and claimed, it being understood that changes in the precise embodiment of the invention herein disclosed can be made within the scope of what is claimed without departing from the spirit of the invention.

55 In the drawings Figure 1 is a section taken on line 1-1 of Fig. 2. Fig. 2 is a

front elevation of the complete eye carrying drums and operating mechanism with the back of the doll head removed. Fig. 3 is a section on line 3-3 of Fig. 2. Fig. 4 is a 60 section on line 4-4 of Fig. 2.

Referring to the drawings, the numeral 1 designates the head of the lay-figure, which in the present instance represents a doll, and it is to be understood may represent the 65 head of any wax display figures that are used in displaying dresses and the like in show windows, said head as usual being provided with the eye apertures 2.

Journaled within the head transversely 70 thereof in the rear of, but in line with the apertures 2 is the main shaft or spindle 3, which has keyed thereupon and rotatable therewith the two eye carrying drums 4 and 5, respectively, said drums being spaced 75 apart, the purpose of which will presently appear, and being retained relatively upon the spindle against longitudinal movement by means of the two spring disks 6 as clearly illustrated in Fig. 2. A spool 7 is disposed 80 upon the spindle or shaft between the respective eye carrying drums 4 and 5 and has rotatably mounted thereon, the eye 8 of the lever or arm 9, which has mounted upon its lower end the weight 10 which forms an operating pendant for rotating the respective drums 4 and 5 as will presently appear.

In order to prevent injury to the head of the lay figure due to the oscillation of the weight 10 and in case the head should be 90 moved too far forwardly, thereby bringing the weight into close contact with the wall thereof, a cushion 11 is positioned as shown in Figs. 1 and 2, in the path of to be engaged by the said weight 10.

95 A band 12 is connected to and carried by the drum 4 adjacent to the space between the respective arms 4 and 5 and is provided with the ratchet teeth 13, which are disposed in the path to be engaged by the arm or rod 100 9, so that when the head is tilted to reclining position, the rod 9 will ride over such teeth without affecting the movement of the drums, but when the head is moved to upright position, said rod 9 will engage one of the ratchet teeth and rotate both drums to bring the next successive pair of eyes into line with the apertures 2.

105 In order to prevent a too far rotation of the respective drums 4 and 5, due to the 110 up-righting of the head 1, and the weight actuated lever or arm 9, a toothed ratchet 14

is connected to the reduced end of the drum 5 and is disposed in the path to be engaged by the pawl 15, so that as soon as the weight 10 assumes the position as shown in Fig. 1, the pawl 15 will engage one of the teeth of the ratchet 14 and thus retain the spindle 3 and drums 4 and 5 against further rotation, until the head has been reclined or tilted rearwardly and again uprighted. These respective drums 4 and 5 are made of any desired material and may or may not have the surface 16, which is non-circular in form and is provided with a plurality of flat surfaces 17, to each of which is connected the imitation eye 18, the respective surfaces 17 of the drums 4 and 5 being so positioned as to be presented in proper alinement, so that each one will present an imitation eye 18 at its respective aperture 2 of the head when the head is in the position as shown in Fig. 1.

From the foregoing description taken in connection with the drawings, it is evident that the respective drums 4 and 5 may carry different colored pairs of eyes, each of said eyes having certain characteristics with relation to the positioning of the pupil and retina thereof or may contain blank places to represent a sleeping lay figure. It is also evident that any form of mechanism may be mounted within the lay figure to automatically rotate the drums 4 and 5, to consecutively or successively display various pairs of eyes, when the figures are used in connection with display figures in windows, and thus not require the reclining operation of the head.

If so desired the head may be pivoted to the body of the lay-figure, and have imparted thereto the desired tilting and uprighting movement to cause the rotation of the drums 4 and 5 at predetermined intervals to make the desired change, in the expression or color of the eyes.

What is claimed is:

1. A lay figure head provided with eye apertures, a rotatable eye carrying member disposed within the head, a plurality of pairs of imitation eyes carried by said member, and means for imparting a step-by-step movement to said member and successively alining a pair of said imitation eyes at a time with the eye apertures of the head.

2. A lay figure head provided with eye apertures, a rotatable eye carrying member disposed within the head, a plurality of pairs of imitation eyes carried by said member, a pendulum pivotally connected to said rotatable member, and means carried by said rotatable member and in coactive relation with said pendulum for imparting a step-by-step movement to said member due to the oscillation of the pendulum for presenting the pairs of imitation eyes, one pair at a time to the apertures of the head.

3. A lay-figure head provided with eye apertures, a shaft journaled transversely of the head, two eye carrying drums carried by and rotatable upon each shaft, a plurality of eyes carried by each drum and disposed in alined pairs upon presentation to the eye apertures of the head, a pendulum disposed between the drums and free to move without relation thereto, and means carried by the drum and disposed in coactive relation with the pendulum to be acted thereupon due to the oscillation of the pendulum to impart step-by-step rotation to the drums.

4. A lay-figure head provided with eye apertures, a shaft journaled transversely of the head, two eye carrying drums carried by and rotatable upon the shaft, a plurality of eyes carried by each drum and disposed in alined pairs upon presentation to the eye apertures of the head, a pendulum swingingly mounted between the drums and free to move with relation thereto, and a ratchet carried by one of said drums and disposed in the path to be engaged by said pendulum during the oscillation of the pendulum to have imparted thereto and the drum a step-by-step rotation.

5. A lay-figure head provided with eye apertures, a rotatable eye carrying member disposed within the head, a plurality of pairs of imitation eyes carried by said member, means for imparting a step-by-step movement to said member and successively alining a pair of said imitation eyes at a time with the eye apertures of the head, and coactive means carried by the rotatable member and the head of the figure to limit the movement of the member during the rotation thereof.

6. A lay-figure head provided with eye apertures, a rotatable eye carrying member disposed within the head, a plurality of pairs of imitation eyes carried by said member, a pendulum pivotally connected to said rotatable member, means carried by said rotatable member and in coactive relation with said pendulum for imparting a step-by-step movement to said member due to the oscillation of the pendulum for presenting the pairs of imitation eyes, one pair at a time to the apertures of the head, and coactive means carried by the rotatable member and the head of the figure to limit the movement of the member during the rotation thereof.

7. A lay-figure head provided with eye apertures, a shaft journaled transversely of the head, two eye carrying drums carried by and rotatable upon the shaft, a plurality of eyes carried by each drum and disposed in alined pairs upon presentation to the eye apertures of the head, a pendulum swingingly mounted between the drums and free to move with relation thereto, a ratchet carried by one of said drums and disposed in

the path to be engaged by said pendulum during the oscillation of the pendulum to have imparted thereto and the drums a step-by-step rotation, and coercive means carried by one of the rotatable drums and the head of the figure to limit the movement of the drum during the rotation thereof.

In testimony that I claim the foregoing as my own, I have hereto affixed my signature in the presence of two witnesses.

JOHN M. DICKSON.
